UNITED STATES PATENT OFFICE.

ALBERT ULLMANN, OF MACON, GEORGIA, ASSIGNOR OF ONE-HALF TO
RAMSDELL INVERTED GAS LAMP COMPANY, A CORPORATION OF
NEW YORK.

GAS-CHECK.

No. 820,885.

Specification of Letters Patent.

Patented May 15, 1906.

Application filed September 13, 1905. Serial No. 278,293.

To all whom it may concern:

Be it known that I, ALBERT ULLMANN, a citizen of the United States, residing at Ma-
5 con, in the county of Bibb and State of Geor-
gia, have invented new and useful Improve-
ments in Gas-Checks, of which the following
is a specification.

This invention relates to gas-checks; and
10 the object thereof is to provide a gas-check
which is particularly adapted for regulating
the flow of gas or for other purposes for
which it is found applicable.

The invention further aims to provide a
15 gas-check which shall be simple in its con-
struction, strong, durable, efficient in its use,
and comparatively inexpensive to manu-
facture.

With the foregoing and other objects in
20 view the invention consists of the novel con-
struction, combination, and arrangement of
parts hereinafter more specifically described,
and illustrated in the accompanying draw-
ings, which form a part of this specification,
25 and wherein is shown the preferred embodi-
ment of the invention, but it is to be under-
stood that changes, variations, and modifica-
tions can be resorted to which come within
the scope of the claims hereunto appended.

30 In describing the invention in detail ref-
erence is to be had to the accompanying
drawings, wherein like reference characters
denote corresponding parts throughout the
several views, and in which—

35 Figure 1 is a vertical sectional view of a gas-
check in accordance with this invention.
Fig. 2 is a detail illustrating the vertically-
movable slide for adjusting the pin-valves
40 shown in Fig. 1. Fig. 3 is a detail of the ro-
tatably and eccentrically mounted member
for operating the slide. Fig. 4 is a view simi-
lar to Fig. 2, showing another form of verti-
cally-movable slide for adjusting the pin-
45 valves, also showing a modified form of valve.
Fig. 5 is an elevation showing the adaptation
of the gas-check in connection with an in-
verted light and with means for shifting the
eccentrically-mounted member. Fig. 6 is a
50 vertical section of a modified form, and Fig. 7
is a detail of the construction shown in Fig. 6.

Referring to the drawings by reference
characters, 1 denotes the body of the gas-
check open at its bottom, as at 2, forming
thereby an inlet for the gas, the wall of said

opening being screw-threaded, as at 3, to per-
mit of connecting the body 1 with a gas-pipe.
(Not shown.) The upper portion of the body
1 of the gas-check is formed in a tapering
manner, as at 4, and has the top thereof
closed with the exception of a plurality of 55
square openings 5, forming the gas-outlets
and through which are adapted to operate
the pin-valves, to be hereinafter referred to.
The body 1 of the gas-check is furthermore
provided with an outwardly-extending sleeve 60
6, forming a bearing for an element of the gas-
check, to be hereinafter referred to.

Arranged within the body 1 of the gas-
check and conforming to the interior shape of
said body 1 is a vertically-movable slide 8,
70 having its top formed with a laterally-extend-
ing protuberance, so as to form the upper
portion of the slide 8 in a substantially cy-
lindrical manner, as at 9, and the said cylin-
drical portion 9 has the top edge thereof pro-
vided with a plurality of tapering pin-valves
10, which are substantially square in cross-
section. The pin-valves 10 are positioned
below the outlets 5 and are adapted to oper-
ate through the said outlets 5, as well as close
the outlets and when operating through said
outlets 5 are adapted to regulate the flow of
gas. The pin-valves 10 are vertically moved
in both directions through the medium of the
slide 8, means being provided in a manner as
hereinafter set forth for vertically moving
the said slide 8, which in turn will carry the
pin-valves therewith. The lower end of the
slide 8 is provided with a laterally-extending
guide member 11, which bears against the in-
ner face of the body 1, provided with an open-
ing 12, which permits of the passage of gas
therethrough, and immediately above the
said member 11 the slide is provided with a
slot 13, in which extends a means for verti-
cally moving the slide to be hereinafter re-
ferred to. The end walls of the slot 13 form
a stop respectively for the movement of the
slide 8 upwardly and downwardly, and there-
by prevent the pin-valves from entirely leav-
ing the gas-outlet openings on the downward
movement of the slide and also prevent the
pin-valves from being forced up too high
through the gas-outlet openings on the up-
ward movement of the slide. The slide 8 is
furthermore provided near its upper end with
a guide 8^a, which engages the inner face of
the body 1, as shown. The guide 8^a is struck

from the slide 8, but any other suitable construction can be employed.

Mounted for rotation within the sleeve 6 is a shaft 14, which extends into the body 1 of the gas-check and also projects from the outer end of the sleeve 6, the latter acting as a bearing for the shaft 14. The inner end of the shaft 14 is enlarged, as at 15, and bears at one end against the inner face of the sleeve 6 and at its other end against the slide 8. The enlarged end 15 of the shaft 14 acts as a means to prevent leakage and also the removal of the shaft 14, and also acts as a means for retaining the slide 8 centrally of the body 1 of the gas-check. The enlarged end 15 of the shaft 14 carries an eccentrically-mounted stud 16, which extends through the slot 13, and when the shaft 14 is rotated the said stud 16 is adapted to shift the slide 8, thereby adjusting the pin-valves 10 in one direction or the other in accordance with the direction in which the shaft 14 is rotated. The projecting end of the shaft 14 carries a thumb-piece 17, of non-conductive material. Said thumb-piece also acts as a means to prevent the shifting of the shaft 14 longitudinally when the check is set up. It will be evident that when the thumb-piece is grasped by the operator and turned in one direction or the other the stud 16 will cause the shifting of the slide 8, and thereby vertically move the pin-valves so as to open and close the gas-outlets or to regulate the flow of gas through the said outlets.

In the construction shown in Fig. 4 the vertically-movable slide is indicated by the reference character 18 and carries upon its upper end a circular plate 19, to which is secured a plurality of vertically-extending pin-valves 20, which are cylindrical in cross-section and operated through the gas-outlets, but in this instance instead of the gas-outlets being square they are circular. The slide 18 is further provided with a laterally-extending protuberance 21 near the top thereof and which acts as a guide, and at the bottom of the slide 18 a laterally-extending guide member 22 is provided, which has an opening 23 to permit of the passage of gas. Immediately above the member 22 a notch 24 is formed in the slide 18, and within the said notch is adapted to operate the eccentrically-mounted pin 16. The construction shown in Fig. 3 is operated in the same manner as that referred to in connection with Figs. 1 and 2.

In Fig. 5 the gas-check is shown in use in connection with an inverted light; but it is evident that the same can be used with an upright light. The showing in Fig. 5 is for the purpose of illustrating a means for operating the gas-checks when the light is suspended overhead. Said means consists of a bar 25, attached to the shaft 14, and depending from the said bar is a pair of chains 26. Stops 27 are provided to arrest the movement

of the rod 24 in either direction. The chains 26 can be dispensed with, if desired.

In the modified construction shown in Figs. 6 and 7 the sleeve 6 is dispensed with, and in lieu of the cylindrical shaft 14 a tapering shaft 28 is employed, which extends through the body 29 of the gas-check and carries on its outer end a thumb-piece 30, which is an integral part of the shaft 28 and is separated therefrom through the medium of the neck 75 portion 31, the latter being integral with the shaft and with the thumb-piece. The employment of the tapering shaft 28 prevents leakage, and the said shaft 28 on its inner end carries an eccentrically-arranged stud 32, which engages in the slot of the slide. The shaft 28 is retained in position through the medium of the shell 33, which is provided with a key-hole-slot 34 and a swaged portion 35, conforming in contour to the outer end of the shaft 28. Otherwise than that as stated the construction of the gas-check is the same as that shown in Fig. 1, the same reference characters being applied thereto. The manner of setting up the shell 33 so as to secure the shaft 31 in position is as follows: The shell 33 is mounted upon the body 29 of the check and turned until the circular part of the key-hole-slot 34 registers with the opening in the body 29, through which passes the shaft 28. The shaft 28 is then passed through the enlarged part of the keyhole-slot and the opening in the body portion, so that the stud 32 will engage in the slot of the slide. The shell 33 is then turned so that the neck 31 will pass into the small part of the keyhole-slot 34 and until the swaged portion 35 will spring over the outer end of the shaft 28, which securely retains the shaft in position, but permits of the shaft being shifted or partly rotated, so as to impart a vertical movement to the slide 8.

Although in Figs. 1, 2, and 6 of the drawings the slide 8 is shown as provided with three pin-valves 10, yet it is evident that two can be used or the number of the pin-valves increased, as desired.

I am aware that a single pin-valve has been employed for regulating the discharge of gas; but in such cases in order that the discharge may be in due quantity the port or exit opening requires to be made so large that the pressure is insufficient to carry the flame to the top of the mantle of an incandescent or Welsbach burner, nor will the gas discharged through a single center port fill the mantle with a glowing light, which is produced when a plurality of ports is employed. When a single central valve or handle-valve is employed and other ports or passages are used in conjunction therewith and unprovided with such valves, they soon become clogged by dust or other matter derived from corrosion of the metal, which at first makes the burner unsatisfactory in use and finally entirely useless, since the single opening or exit, 130

as before stated, cannot furnish sufficient gas to give a satisfactory light. The advantage of a plurality of pin-valves over the construction just set forth is fully described in Letters Patent granted to me November 15, 1904, No. 775,156, upon which the structure herein disclosed is an improvement. In the structure shown in Letters Patent No. 775,156 a vertically-movable screw is employed to operate a plate carrying the pin-valve, the operation being from the bottom of the body of the check and the supply of gas being taken in through the side of the body of the check, whereas in the construction set forth in this application the adjustment of the pin-valves is more readily had, owing to the manner of employing the slide in connection with the eccentrically-mounted operated means therefor, for the reason that by simply imparting a half-turn to the thumb-piece the valves will be moved in one direction and by shifting the thumb-piece a half-turn in another direction the valves will be carried therewith. Furthermore, in the construction embodied in this application gas is supplied up through the bottom and not through the side of the body of the check, which has been found to be more advantageous. Further advantages of the employment of a plurality of pin-valves are as follows: impossibility of becoming clogged, a brilliancy of white light caused by proper combustion, the latter being established by the construction of perfect regulation, and securing by perfect combustion economy of the use of gas.

Small bodies are easier and quicker mixed than large ones. Therefore the smaller the exit-openings are the finer the stream of gas will be and the better and quicker it will unite with the oxygen of the atmosphere. The adjustment of the pin-valves insures perfect regulation, no matter what the quality and pressure of gas may be, so that perfect combustion is thereby produced, causing a brighter and whiter light, and there being no waste of gas by smoke economy in the use of gas is established. This benefit is being further enhanced by the annular or square passage of the gas around the pins and which causes the gas stream to be still more thinned out, as owing to the fact that instead of having a solid stream it is a hollow one and which is essentially filled with air as it leaves the outside of the pins.

Having thus fully described my invention, what I claim as new, and desire to secure by Letters Patent, is—

1. In a gas-check, a body portion open at its bottom and having its top provided with a plurality of gas-outlets, a vertically-movable flat slide arranged within said body portion at one side thereof and having an opening and a laterally-extending integral guide member, a rotatable shaft extending within the body of the check and provided with an ec-

centrically-mounted stud projecting through said opening, said stud adapted to engage said slide and shift the same when the shaft is rotated, and a plurality of pin-valves carried by said slide and adapted to open or close 70 said outlets when the slide is shifted.

2. A gas-check having a series of gas-outlets, a vertically-movable flat slide carrying a plurality of pin-valves for opening and closing said outlets, said slide further provided 75 with a guide member extending at right angles thereto and having an opening, and means engaging in the slide for vertically moving the same.

3. A gas-check having a series of gas-outlets, a vertically-movable slide carrying a plurality of pin-valves for opening and closing said outlets, said slide further provided at its lower end with a guide member extending at right angles thereto and having an 85 opening, and a shiftable and eccentrically-mounted means engaging in said slide for vertically moving the same when the said means is shifted.

4. A gas-check comprising a body portion 90 communicating at one end with a gas-supply and at its other end provided with a plurality of gas-outlets, a plurality of vertically-movable pin-valves arranged within said body portion and adapted to open and close the said 95 outlets, a vertically-movable flat slide carrying the said pin-valves and bent at its lower end to provide a guide member and said slide further provided with an opening, and a shiftable and eccentrically-mounted means supported by the body portion and engaging in 100 said opening for vertically moving the slide when said means is shifted.

5. A gas-check comprising a body portion having a part thereof cylindrical in contour 105 and the other part thereof tapering, said cylindrical part of said body portion communicating with a gas-supply and said tapering part provided with a plurality of gas-outlets, a vertically-movable flat slide arranged within 110 said body portion and having the side edges thereof conforming in contour to the shape of the body portion, a plurality of pin-valves carried by said slide and adapted to open and close the said outlet, and shiftable and eccentrically-mounted means engaging in said slide 115 for vertically moving it when said means is shifted.

6. A gas-check comprising a body portion having a part thereof cylindrical in contour 120 and the other part thereof tapering, said cylindrical part of said body portion communicating with a gas-supply and said tapering part provided with a plurality of gas-outlets, a vertically-movable flat slide arranged with- 125 in said body portion and having the side edges thereof conforming in contour to the shape of the body portion, a plurality of pin-valves carried by said slide and adapted to open and close the said outlets, said slide provided with 130

- 1 a curvilinear guide member having an opening therethrough, and a shiftable and eccentrically-mounted means engaging in said slide and adapted to vertically move it when the 5 said means is shifted.
7. A gas-check comprising a body portion communicating at its bottom with a gas-supply and having its top provided with a plurality of gas-outlets, a vertically-movable 10 flat slide arranged within said body portion at one side thereof and provided with an opening, a plurality of pin-valves carried by the slide and adapted to open and close said outlets, a shaft extending into said body portion 15 and provided with an enlarged end bearing against said slide and further provided with an eccentrically-mounted member extending in said opening and adapted when the shaft is shifted to vertically move the 20 slide, a thumb-piece carried on the outer end of said shaft, and means for securing the shaft to the body portion.
8. A gas-check comprising a body portion having a plurality of gas-outlets, a vertically-movable 25 slide arranged therein and having its upper portion substantially cylindrical in contour, said cylindrical portion having the top edge thereof provided with a plurality of upwardly-extending pin-valves adapted 30 to open and close said outlets, said slide having its bottom formed with a laterally-extending curvilinear guide member provided with an opening and said slide at a point in close proximity to said guide member formed 35 with a slot, and a shiftable and eccentrically-mounted means supported by the body portion of the gas-check and engaging in said slide and adapted when shifted to vertically move the slide.
- 40 9. A gas-check having a plurality of openings substantially square in contour and forming gas-outlets, a vertically-movable flat slide arranged within said body portion, a plurality of pin-valves carried by said slide, 45 substantially square in cross-section and adapted to open and close the said outlets, and means for vertically moving the said slide.
10. A gas-check having a plurality of openings substantially square in contour and forming gas-outlets, a vertically-movable flat slide arranged within said body portion, a plurality of pin-valves carried by said slide, substantially square in cross-section 55 and adapted to open and close the said outlets, said slide provided with a slot and with a guide member having an opening therein, and a shiftable and eccentrically-mounted means engaging in said slot for vertically moving the slide when said means is shifted.
11. In a gas-check, the combination with a body portion provided with a plurality of outlets, of means for opening and closing said outlets, said means consisting of a vertically- 60

movable slide terminating at its top in a laterally-extending cylindrical portion provided with a plurality of vertically-extending pin-valves. 65

12. In a gas-check, the combination with a body portion provided with a plurality of outlets, of means for opening and closing said outlets, said means consisting of a vertically-movable slide terminating at its top in a laterally-extending cylindrical portion provided with a plurality of vertically-extending pin-valves and said slide at its bottom terminating in a laterally-extending guide member. 70 75

13. In a gas-check, the combination with a body portion provided with a plurality of outlets, of means for opening and closing said outlets, said means consisting of a vertically-movable flat slide terminating at its top in a laterally-extending cylindrical portion provided with a plurality of vertically-extending pin-valves and said slide at its bottom terminating in a laterally-extending guide member provided with an opening. 80 85

14. In a gas-check, the combination with a body portion provided with a plurality of outlets, of means for opening and closing said outlets, said means consisting of a vertically-movable flat slide terminating at its top in a laterally-extending cylindrical portion provided with a plurality of vertically-extending pin-valves and said slide terminating at its bottom in a laterally-extending curvilinear flange provided with an opening. 90 95

15. In a gas-check, the combination with a body portion provided with a plurality of outlets, of means for opening and closing said outlets, said means consisting of a vertically-movable flat slide terminating at its top in a laterally-extending cylindrical portion provided with a plurality of vertically-extending pin-valves and said slide having a slot and terminating at its bottom in a laterally-extending curvilinear guide member provided with an opening, combined with means engaging in said slot for vertically moving the slide. 100 105 110

16. The combination with a body portion having an outlet, of a valvular means for opening and closing said outlet, operating means for said valvular means, and a slotted shell engaging said body portion for retaining said operating means in position. 115

17. The combination with a body portion having an outlet, of a valvular means for opening and closing said outlet, operating means for said valvular means, and a shiftable and detachable slotted shell engaging said body portion for retaining said operating means in position. 120

18. A gas-check comprising a body portion having a series of gas-outlets, a vertically-movable slide carrying a plurality of pin-valves for opening and closing said outlets, means engaging in said slide for vertically 125

moving the same, and a slotted shell engaging the body portion and operating means for retaining the latter in position.

19. A gas-check comprising a body portion having a series of gas-outlets, a vertically-movable slide carrying a plurality of pin-valves for opening and closing said outlets, means engaging in the slide for vertically moving the same, and a shiftable and detachable shell provided with a keyhole-slot and engaging said body portion and operating means for retaining the latter in position.

20. A gas-check comprising a body portion having a series of gas-outlets, a movable slide carrying a plurality of pin-valves for opening and closing said outlets, a shiftable and eccentrically-mounted means engaging in said slide for moving the same when said means is shifted, and a slotted shell engaging said body portion and operating means for retaining the latter in position.

21. A gas-check comprising a body portion having a series of gas-outlets, a movable slide carrying a plurality of pin-valves for opening and closing said outlets, a shiftable and eccentrically-mounted means engaging in said slide for moving the same when the said means is shifted, and a shell provided with a keyhole-slot and engaging said body portion and operating means for retaining the latter in position.

22. A gas-check comprising a body portion communicating at its bottom with a gas-supply and having its top provided with a plurality of gas-outlets, a reciprocating slide arranged within said body portion, a plurality of pin-valves carried by the slide and adapted to open and close said outlets, a shaft extending through said shell and into said body portion and provided with an enlarged end bearing against said slide and further provided with an eccentrically-mounted member extending in the slide and adapted when the shaft is shifted to reciprocate the slide, a thumb-piece carried on the outer end of said shaft, and a shell surrounding the body por-

tion and engaging the shaft for retaining the latter in position.

23. A gas-check having a series of gas-outlets, a vertically-movable slide carrying a plurality of pin-valves for opening and closing said outlets, said slide bent at its lower end to form a guide member and further provided near the top thereof with a guide member struck therefrom, said guide members extending in the same direction and the lower of said members provided with an opening, and a shiftable and eccentrically-mounted means engaging in said slide for vertically moving the same when the said means is shifted. 50 55 60

24. A gas-check having a series of gas-outlets, a vertically-movable slide carrying a plurality of pin-valves for opening and closing said outlets, said slide provided at its bottom with an opening and further provided at its bottom with a laterally-extending guide and near the top of the laterally-extending guide, and a shiftable and eccentrically-mounted means engaging in said opening for vertically moving the same when the said means is 70 shifted. 65

25. A gas-check comprising a body portion, a vertically-movable slide arranged in said body portion at one side thereof and provided with a pair of guides, a plurality of pin-valves carried by the slide and adapted to open and close said outlets, and a shaft provided with an enlarged end arranged in the other side of said body portion and bearing against said slide and further provided with 75 80 85 an eccentrically-mounted member extending in said slide and adapted when the shaft is operated to vertically move the slide, thereby shifting the pin-valves to and from closure position.

In testimony whereof I have hereunto set my hand in presence of two subscribing witnesses.

ALBERT ULLMANN.
